UNITED STATES PATENT OFFICE.

ALTON L. BAUGHMAN, OF WOLFLAKE, INDIANA.

RENEWABLE SOLE FOR WORN PLANTER-SHOES.

No. 907,440.

Specification of Letters Patent.

Patented Dec. 22, 1908.

Application filed July 14, 1908. Serial No. 443,491.

To all whom it may concern:

Be it known that I, ALTON L. BAUGHMAN, a citizen of the United States, residing at Wolflake, in the county of Noble and State 5 of Indiana, have invented a new and useful Renewable Sole for Worn Planter-Shoes, of which the following is a specification.

This invention has relation to soles for planter shoes, and it consists in the novel 10 construction and arrangements of its parts, as hereinafter shown and described.

The object of the invention is to provide a renewable sole for planter shoes, whereby when one sole is worn out it may be replaced 15 by another, thereby saving considerable expense, as it avoids the necessity of equipping the planter with an entire new shoe when the sole thereof has become worn out. Again by reason of the fact that the shoes used 20 upon ordinary corn planters and the like are subjected to much wear and abrasion during the course of planting, the said shoes frequently become worn to such an extent as to become useless, and, when this occurs, considerable 25 expense is entailed by providing new shoes. Frequently the shoes are worn after it has become impossible to obtain shoes of similar character or pattern for the reason that the shoes vary in pattern during 30 different seasons.

It is therefore the object of the present invention to provide a renewable sole for such shoes also, and when the shoe has become worn the said sole may be applied thereto, 35 thus prolonging the life of the shoe and saving the expense as above stated.

With this object in view the renewable sole consists of plates of like pattern and dimension which are joined together laterally 40 at their lower portions and which are spread apart at their upper portions for the reception of the lower portion only of the planter shoe. The lower edge of the sole conforms to the original configuration of the 45 lower edge of the planter shoe (provided it is applied to a worn planter shoe), or in case the sole is applied to a planter shoe in the first instance the lower edge of the said sole is a continuation of the curvature of the 50 lower forward edge of the planter shoe.

In the accompanying drawing, Figure 1 is a side elevation of a planter shoe with the renewable sole attached thereto. Fig. 2 is a perspective view of the sole detached, and

Fig. 3 is a rear end elevation of the sole detached.

In Fig. 1 of the drawing the numeral 1 represents the planter shoe and the dotted line 2, represents the edge to which the lower portion of the said shoe has been worn during 60 its use, or the lower edge of the shoe as it may be made in the first instance. The grain-tube 3, is mounted upon the rear end portion of the shoe 1. The renewable sole consists of the plates 4, which are of like configuration and like dimensions. Said plates 65 4, are secured together at their lower portions by welding, riveting, or otherwise, as at 5, and the lower edges 6, of the said plates conform to the original configuration of the 70 lower edge of the planter shoe 1, or if the plates are applied to the shoe in the first instance, the lower edge 6, thereof is a continuation of the curvature of the lower forward edge of the said shoe. The upper 75 portions of the plates 4, are spaced apart for the reception of the lower portion of the shoe 1, and the upper portions of the said plates are secured to the shoe 1, by means of the rivets 80 7, which pass transversely through the said shoe and the said plates.

From the above description it is obvious that when the planter shoe 1, becomes worn to such an extent as to be practically useless, that the shoe may be applied thereto in the 85 manner as illustrated in Fig. 1, or should the planter shoe in the first instance be made substantially as shown in Fig. 1, the sole may be applied thereto and in both instances the lower edge 6, of the sole will be a continuation 90 of the lower forward edge of the shoe, and the shoe and sole combined will have the general configuration of an ordinary planter shoe. Thus by applying the sole to a worn planter shoe the said shoe is transformed 95 from a worthless condition into a serviceable one, and may be used indefinitely, for as soon as the sole becomes worn it may be removed and a new sole substituted in its stead.

While the description herein given has 100 been directed particularly to planter shoes, it is obvious that the sole may also be advantageously applied to listers or similar implements.

Another advantage gained by the present 105 construction of the sole is that no part of the sole projects beyond the upper edge of the shoe 1, when the sole is applied thereto, and

consequently no shoulders or angles are provided which may accumulate soil and thus obstruct the proper operation of the shoe or add undue draft to the implement. It may be added further that by reason of the fact that the lower portions of the blades 4, are joined together laterally that the metal throughout the said area is substantially doubled, and consequently the lower portion 10 of the shoe possesses greater wearing qualities than if the metal of which the sole is composed were of the same thickness throughout. At the same time the said sole does not add undue weight to the shoe for the reasons that 15 the portions of the sole which overlap the side portions of the shoe are relatively thin. It will also be seen that by reason of the fact that the lower portion of the shoe 1, is seated within the sole and has contact with the 20 plate 4, along the lines thereof where they begin to approach each other, that any jarring to which the sole may be subjected is not transmitted in an entirety to the rivets 7, which secure the sole to the shoe. That is to 25 say, the configuration of the sole in a great measure protects the rivets 7 against jarring and rough usage.

Having described my invention, what I claim as new, and desire to secure by Letters Patent is:—

30

In combination with a planter shoe having the lower rear edges of its side portions spaced apart, a renewable sole, comprising plates of like pattern and dimensions integrally joined together laterally at their lower 35 portions and spaced apart at their upper portions, to receive the lower portions of the sides of the shoe said plate having intermediate inclined portions which form rests for the lower edges of the shoes, the lower edges 40 of the plates conforming to the curvature of the lower forward edge portion of the shoe, the upper edges of the sole terminating short of the upper edges of the shoe, and securing devices passing transversely through the 45 sides of the sole and the shoe.

In testimony that I claim the foregoing as my own, I have hereto affixed my signature in the presence of two witnesses.

ALTON L. BAUGHMAN.
